FOREIGN PATENT DOCUMENTS

JP D1722444 * 8/2022

Primary Examiner — Daniel J Domino*Assistant Examiner* — Lee D. Starr(57) **CLAIM**

The ornamental design for a mask rope as shown and described.

DESCRIPTION

FIG. 1 is a front view of a mask rope showing my new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a perspective view thereof;

FIG. 8 is a perspective view thereof, shown in an in-use configuration;

FIG. 9 is a front view in open state;

FIG. 10 is a back view in open state;

FIG. 11 is a front view of a mask rope applied to an alternate mask; and,

FIG. 12 is a front view of a mask rope applied to an alternate mask.

The broken lines shown on the drawings depict portions of the mask rope that form no part of the claimed design.

1 Claim, 9 Drawing Sheets(56)
